UNITED STATES PATENT OFFICE.

WILLIAM B. FULTON, OF MIDDLETOWN, OHIO.

PAPER DRIER AND THE LIKE.

Application filed May 20, 1925. Serial No. 31,520.

This invention relates to improvements in paper driers, having particular reference to improved means for extracting air and the condensate from steam injected into drier 5 rolls to maintain the same at a raised temperature suitable for drying the paper web as the same traverses the rolls.

The object attained in the practice of the invention is greater uniformity of temperature of the rolls and therefore more rapid 10 and uniform drying of the paper.

To this end, my invention consists in means for controlling injection of the steam into the rolls, in equalizing distribution of 15 the steam in the rolls, and means for extracting the steam condensate and air thus maintaining even temperature of the rolls at any desired point.

In the accompanying drawings:

20 Fig. 1 is a longitudinal sectional view of a paper drier roll illustrating my invention as applied thereto;

Fig. 2 is a cross-sectional view of the drier taken on line 2—2 of Fig. 1;

25 Figs. 3 and 4 are detail views of valve mechanisms for regulating the injection of steam into the drier rolls;

Fig. 5 is a detail of the valve controlling mechanism.

30 As here shown, the drier 1 including the journals 2 and 3 upon which the roll is rotatably supported, and the gear 4 for rotating the drier are of well known conventional construction.

35 My invention, as applied to the drier roll, consists of a fixed tube 5 disposed axially in drier 1, extended through journal 3 at one end and connected to a steam line 6, and extending into journal 2 at the other end and 40 there provided with a lubricating mechanism 7.

The tube 5 is provided with a series of 45 valves 8—9 and 10 operatively connected to a rod 11 and by means of the rod to valve regulating mechanism 12 which consists of a rod actuating member 13 for shifting the rod axially, the actuating member being pivotally connected to the rod as at 14 and fulcrumed on an outwardly extended bracket 50 15 as at 16, the bracket and the rod actuating member 13 being adapted to rotate with rod 11.

Each of the valves 8 and 9 is provided 55 with a slideable shutter 17 connected to rod 11 as at 11^a and having apertures 18 therein adapted to register with ports 19, and an

intermediate port 20 in tube 5 accordingly as the shutter is shifted in one direction or the other relative to the ports. The relation of shutter 17 to the ports in valve 8 is just the opposite from that of the shutter in valve 9, that is to say, when one of the ports 19 in valve 8 is full-open the corresponding port 19 in valve 9 is full-closed, the same relative relation of the valves being effected in all adjustments of the valves for a purpose which will presently be described.

Valve 10 is also provided with a shutter 21 connected to rod 11 as at 11^b in a manner to adapt the shutter to be actuated rotatably but not axially of tube 5, the valve differing in this respect from valves 8 and 9 in which the shutters 17 operate axially but not rotatably of the tube. Shutter 21 is provided with ports 22 adapted to be moved into register, upon rotation of shutter 21, with corresponding ports 23 in tube 5 to any desired extent as determined by rotation of the valve adjusting rod 11, the extent of adjustment of the valve being indicated by a pointer 24 registering on the graduated scale 24^a, the adjustment of valves 8 and 9 being indicated by a pointer 25 registering on the scale 25^a.

The function of valves 8, 9 and 10 is to regulate the volume of steam introduced into the drier through tube 5 and to control the distribution of the steam in the drier so that the heating of the drier can be maintained uniform throughout its length, thus to effect a uniform drying action on the paper as it 50 traverses the drier units. It will be observed that valves 8 and 9 are adjustable independently of valve 10 and, vice versa, valves 8 and 9 being adjusted in unison one with the other but, as stated, oppositely one of the other with respect to opening and closing of the valve ports. Thus introduction and distribution of the steam in the drier can be controlled effectually and heating of the drier maintained uniform by simple manipulations of the valve actuating member 13.

To heat the drier units by steam it is necessary that the condensate from the steam and non-condensable gases or air be removed from the drier as accumulation of water and air in the drier prevents effective heating of the same. The best heating conditions are obtained when the condensate and air are maintained at the minimum, that is to say, when any accumulation of water and air 100 in the drier is prevented.

To this end, I employ improved means for

- extracting the water and air from the drier consisting of a drain line 26 extended into the drier on the line of its axis and including depending branches 27 each provided with a scoop or pan-shaped receptacle 28 pivoted as at 29 on the free ends of branch pipes 27 in a manner to permit the forward edge of the scoops to contact with the drier drum thus to cause any water in the bottom 10 of the drier to be taken up by scoops. It will be observed that the capacity of the drain line increases outwardly, the ratio of increase being such that the capacity of the line at all points will be more than equal to 15 the capacity of the branches 27 discharging therethrough.
- Discharge of the condensate and air through line 26 is effected by maintaining relative pressures in the steam line 5—6 and 20 the discharge line 26, the steam line and drier carrying a higher pressure than the discharge line, the discharge of water from the drier being constant as long as the water rises to the level of ports 30 at the lower 25 extremities of the branch pipes 27, which are preferably curved rearwardly, as illustrated in Fig. 2, to relieve the pipes of strain resulting from the action of the water on scoops 28. The head pressure of the water 30 on the scoops also has the effect of causing the water to rise in pipes 27 and discharged through the drain line, thus acting to further reduce the accumulation of water in the driers.
- 35 From the foregoing detailed description and the illustrations of the drawings, the construction and operation of my improved drier drainage will be readily understood. It will be seen that the means afforded for 40 uniform heating of the drier units will be effective to attain the objects of my invention as herein set forth.
- Having described my invention, I claim:
1. A paper drier including in combination 45 with a drier roll a steam line extended into said roll, and a valve arranged in said line within the roll for controlling steam admitted into the roll whereby to regulate heating thereof.
  - 50 2. A paper drier including in combination with a drier roll a steam line extended into said roll, a valve arranged in said line within the roll for controlling steam admitted into the roll whereby to regulate heating thereof, and means arranged externally of the roll for adjusting said valve.
  - 55 3. A paper drier including in combination with a drier roll a steam line extending into said roll, a valve arranged in said line with- 60 in the roll for controlling steam admitted into the roll whereby to regulate heating thereof, and means arranged externally of the roll for adjusting said valve including means to indicate the extent of adjustment thereof.

4. A paper drier including in combination with a drier roll a steam line including a tubular portion extended into said roll, a plurality of valves arranged slidably upon the tubular portion of said line for controlling steam admitted into the roll whereby to regulate heating thereof, and means arranged externally of the roll for adjusting said valves.

5. A paper drier including in combination with a drier roll a steam line including a tubular portion extended into said roll, a plurality of valves arranged in said tubular portion and adapted to be adjusted to function oppositely one of the other to control steam admitted to the roll whereby to regulate heating thereof, and common means external of the roll for adjusting the valves.

6. A paper drier including in combination with a drier roll a steam line including a tubular portion extended into said roll, a plurality of valves arranged in said tubular portion, spaced one from another and adapted to be adjusted to control distribution of steam admitted to the roll to effect heating thereof, and means external of the roll for adjusting the valves.

7. A paper drier including in combination with a drier roll a steam line including a tubular portion extended into said roll, a port in said tubular portion and a part adjustable relative to said port to open and close the same to control steam admitted to the roll whereby to effect heating thereof, and means external of the roll for adjusting said port.

8. A paper drier including in combination with a drier roll a steam line including a tubular portion extended into said roll, a plurality of valves arranged in said tubular portion, certain of the valves being adjustable axially and rotatably respectively of the tubular portion whereby to control distribution of steam admitted to the roll and to effect uniform heating thereof, and means external of the roll common to said valves for regulating the same.

9. A paper drier including in combination with a drier roll a steam line including a tubular portion extended into said roll, a plurality of valves arranged in said tubular portion, certain of the valves being adjustable axially and rotatably respectively of the tubular portion whereby to control distribution of steam admitted to the roll and to effect uniform heating thereof, and means external of the roll common to said valves for regulating the same including means to indicate the extent of said regulation.

10. A paper drier including in combination with a drier roll, a steam line including a tubular portion extended into said roll, a valve in said tubular portion for controlling steam admitted into the drier roll through said line to effect heating of the roll, and

valve and adjusting means arranged external of the roll and extended to said valve within said tubular portion.

11. A paper drier including in combination with a drier roll, a steam line including a portion extended into said roll concentrically to the axis thereof, a valve in said portion for controlling steam admitted into the roll through said line to effect heating of the roll, and valve adjusting means external of the roll and extended to said valve through said portion.

12. A paper drier including in combination with a drier roll, means for injecting steam into said roll, a discharge line connected to the roll to remove the steam condensate and air therefrom, said line including a curved depending branch having a port and a member adapted to take-up the condensate from the bottom of said roll and to coat with said port in removing the same from the roll.

13. A paper drier including in combination with a drier roll, means for injecting steam into said roll, a discharge line connected to the roll to remove the steam condensate and air therefrom, said line including a depending branch having a port and a member adapted to take-up the condensate from the bottom of the roll and to raise the same to the level of said port.

14. A paper drier including in combination with a drier roll, a steam line connected to said roll whereby to effect heating thereof, a discharge line connected to the roll to remove the steam condensate and air therefrom, said line including a plurality of depending branches each having a port and a member adapted to scoop the condensate from the bottom of the roll and to raise the same to the level of said ports.

15. A paper drier including in combination with a drier roll, a steam line connected to said roll whereby to effect heating thereof, a discharge line connected to the roll to remove the steam condensate and air therefrom, said line having a lesser pressure determined relative to the pressure of the steam line to effect outward flow of the condensate and air through the discharge line, and

means comprising a valve within the drier roll for regulating the distribution of steam within the drier roll.

16. A paper drier including in combination with a drier roll, a steam line connected to said roll whereby to effect heating thereof, a discharge line connected to the roll to remove the steam condensate and air therefrom, said line including a depending branch having a port and a member pivoted on said branch and adapted to contact with the bottom of the drier roll to take-up and raise the condensate to the level of said port whereby to effect the discharge thereof.

17. A paper drier including in combination with a drier roll, a steam line connected to said roll whereby to effect heating thereof, a discharge line connected to the roll to remove the steam condensate and air therefrom, said line including a plurality of depending branches each communicating with the bottom of the drier roll to take-up the condensate, the combined capacity of said branches being no greater than the capacity of said main line.

18. A paper drier including in combination with a drier roll, a steam line extended into said roll concentrically to the axis thereof, a discharge line for the steam condensate and air extended into the roll through the steam line and having depending branches extended outwardly of the steam line and communicating with the bottom of the roll whereby to take-up the condensate and air.

19. A paper drier including in combination with a drier roll, a steam line connected to said roll whereby to effect heating thereof, a discharge line connected to the roll to remove the steam condensate and air therefrom, said line including a depending branch having a port and a member, as a scoop, set oppositely to the rotation of the roll and acting to retard the movement of the condensate incident to rotation of the roll and to raise the same to the level of said port whereby to effect extraction thereof from the roll.

In testimony whereof, I affix my signature.

WILLIAM B. FULTON.
